UNITED STATES PATENT OFFICE.

JEAN REY, OF PARIS, FRANCE.

DESIGN FOR A MIRROR FOR PROJECTORS.

56,679.

Specification for Design.

Patented Nov. 23, 1920.

Application filed October 20, 1919. Serial No. 332,126. Term of patent 3½ years.

To all whom it may concern:

Be it known that I, JEAN REY, a citizen of the Republic of France, residing at Paris, France, have invented a new, original, and ornamental Design for a Mirror for Projectors, of which the following is a specification.

The drawing is a front view of a mirror for projectors embodying my design.

The design consists of a reflector having a

circle traced at the center of the mirror, in which circle is inscribed a vignette.

I claim:—

The ornamental design for a mirror for projectors as shown and described.

JEAN REY.
